UNITED STATES PATENT OFFICE

111,183

DESIGN FOR A SMOKING STAND

John K. Milton, Chicago, Ill.

Application April 7, 1938, Serial No. 76,360

Term of patent 14 years

To all whom it may concern:

Be it known that I, John K. Milton, a citizen of the United States, residing at Chicago, in the county of Cook and State of Illinois, have invented a new, original, and ornamental Design for a Smoking Stand, of which the following is a specification, reference being had to the accompanying drawing, in which:—

Fig. 1 is a frontal perspective view of the smoking stand showing my new design;

Fig. 2 is a side elevation;
Fig. 3 is a top plan view end;
Fig. 4 is a section on the line 4—4 of Fig. 2.
I claim:—

The ornamental design for a smoking stand, as shown.

JOHN K. MILTON.
